UNITED STATES PATENT OFFICE.

THOMAS A. ROHDE, OF TIMOTHY, WISCONSIN.

CHEESE RING.

1,411,066.

Specification of Letters Patent. Patented Mar. 28, 1922.

Application filed August 6, 1921. Serial No. 490,307.

To all whom it may concern:

Be it known that I, THOMAS A. ROHDE, a citizen of the United States, and resident of Timothy, in the county of Manitowoc and 5 State of Wisconsin, have invented certain new and useful Improvements in Cheese Rings; and I do hereby declare that the following is a full, clear, and exact description thereof.

10 My invention refers to cheese rings and associated parts, and it has for its objects to provide a simple, economical and effective structure wherein a slip ring is utilized having its edges lapped to form a bead which 15 is offset from the inner surface of the ring, whereby said surface will present an uninterrupted face to the cheese and thus avoid a seam or joint therein.

Another object of my invention is to provide in combination with the offset seam of 20 the ring, a hoop, the enlarged ring receiving section of which has a longitudinal groove therein for the reception of the offset hoop seam or bead, whereby the parts can readily be assembled or withdrawn, and whereby 25 the structure, as a whole, will maintain its proper relations and not be subject to extreme wear due to usage, cramping being avoided, which is the particular objection of 30 the general type of rings.

With the above objects in view, the invention consists in certain peculiarities of construction and combination of parts as are hereinafter set forth with reference to 35 the accompanying drawings and subsequently claimed.

In the drawing,

Figure 1 represents a fragmentary view of 40 the upper portion of a hoop and ring embodying the features of my invention, the parts being partly broken away and in section to more clearly illustrate details of construction.

Figure 2, a similar sectional view of the 45 hoop with the ring removed, the section being indicated by line 2—2 of Figure 3, showing particularly the longitudinal groove formed in the ring receiving section of the hoop, and

50 Figure 3, a plan view of the hoop and ring, particularly showing the nested engagement between the offset bead or lapped joint of the ring and its hoop groove.

Referring by characters to the drawings, 1 55 represents the tapered body section of a standard hoop, the upper portion of which

is enlarged from a ring receiving cuff 2, which cuff is merged inwardly to the body section and thereby forms a seating shoulder 2' for the ring. The ring cuff 2 is formed 60 with a longitudinal outwardly offset groove 4 extending from the shoulder 2' to the mouth of the cuff. This groove is provided for the reception of an exteriorly offset bead 5 of a slip ring 6, which ring, as shown in 65 Figure 3, is fitted snugly into the ring cuff. One of the edges of the bead 5 is outwardly offset, as shown at α , to form a lapped joint in connection with the inner longitudinally divided edge 5' of the seam of bead, the edge 5' being fitted into the countersink thus 70 formed to produce an uninterrupted inner surface for the reception of the cheese.

By providing the lapped joint of the ring with an outwardly offset bead as shown, the 75 parts can readily be assembled and when pushed into the cuff, the joint will be closed up tightly. At the same time, the ring can readily be inserted into the cuff portion of the body, due to the fact that the longitudinal groove α permits nesting of the bead while at the same time the groove is of sufficient cross sectional area with relation to the corresponding area of the bead as to permit 80 ready insertion of the bead, due to the clearance space. Thus in fitting the ring to the mouth of the hoop, cramping of the parts is 85 avoided and when said ring is so fitted, it can be readily extracted when desired, the lapped joint separable seam or bead permitting 90 contraction and expansion of the ring when it is inserted or extracted.

It will also be observed that the groove 4, being stamped from the sheet metal body of 95 the hoop, causing an exterior offset, this offset will be protected due to the fact that it is preferably arranged in alignment to the handles γ of the hoop.

While I have shown one simple exemplification of my invention, it is understood 100 that I may vary the structural features and dimensions within the scope of the claims.

I claim:

1. A metallic cheese hoop, the body portion of which terminates with an expanded 105 cuff portion for the reception of a ring, the cuff portion being merged into the body portion of the hoop to form a shoulder, a slip ring adapted to be fitted into the cuff portion of the hub, the edges of the ring being 110 overlapped and exteriorly offset to form a bead, whereby a smooth inner surface is

maintained for the reception of cheese produced, and a longitudinal groove extending to the base of the cuff for nested engagement with the offset ring bead.

5 2. A metallic cheese hoop having a longitudinal groove extending a predetermined distance from its mouth, and a split ring adapted to be fitted into the mouth of the hoop, the split ring having its edges over-

lapped exteriorly to form an uninterrupted inner surface, the overlapped offset edges of said ring being nested within the longitudinal groove of the hoop.

In testimony that I claim the foregoing I have hereunto set my hand at Timothy, in the county of Manitowoc and State of Wisconsin.

THOMAS A. ROHDE.
